AUTOMATIC FORGING OR PRESSURE
MACHINEHugh Dean, Detroit, Mich., assignor to General
Motors Corporation, Detroit, Mich., a corpora-
tion of Delaware

Application May 11, 1932, Serial No. 610,564

3 Claims. (Cl. 78—99)

This invention relates to automatic forging presses in which the article to be forged is carried through the press by means of the scrap or excess material which projects or extends away from the finished article after it has been forged.

The object of the press is to use a forging method to shape the piece of work instead of the usual rolling process to form the piece of stock. It has been found in practice that in making small articles they can be made quicker and better by a forging process than by the use of the rolling method.

In the machine of the present invention, the blanks are fed at one face of the press and are automatically fed into the machine by means of vertically and horizontally reciprocable feeder bars. These feeder bars feed the work or pieces of stock one at a time from the feed table or hopper at one face of the press and move them in a step by step movement through the machine. The feeder bars are positioned at the sides of the press or machine and in the present invention, one bar at each side is used. The forged article and the excess metal or scrap is discharged from the rear of the machine. The stock is of sufficient length so that it may be picked up at its ends by the feeder bars in its passage through the machine and after it has received the impress of the first set of dies the heated bar of stock becomes somewhat elongated and is, therefore, the more easy to be taken by the feeder bars and passed through the press by a step by step movement. The work or pieces of stock is fed into the machine by a distributor so that but one piece is fed at a time. The dies are arranged in pairs and successive pieces of stock will be fed to alternate dies. This eliminates excessive wear on the dies.

On the drawings:

Figure 1 is a front or face view of the press with the invention applied, the parts being broken away clearer to illustrate the cam for driving the press.

Figure 2 is a side view of the structure of Figure 1.

Figure 3 is a side view of a portion of the press taken on the line 3—3 of Figure 1, with parts broken away better to illustrate the structure.

Figure 4 is a plan view of the structure of Figure 3 with upper die removed, and taken on the line 4—4 of Figure 1.

Figure 5 is an enlarged transverse sectional detail view taken on the line 5—5 of Figure 3.

Figures 6 and 7 represent an enlarged sectional view longitudinally of the machine taken sub-

stantially on line 6—6 of Figure 5. Figure 7 is a continuation of the structure of Figure 6.

Figure 8 is a detailed view to illustrate the movements of the feeder bars and cam extension bars.

Figure 9 is a perspective view of the various steps in the formation of the article from the bar of stock to the finished product.

Figure 10 is a sectional detailed view on the line 10—10 of Figure 7.

Figure 11 is a side view of a mechanism for holding the work when the dies are being withdrawn to prevent the work from bouncing out of the dies or out of its regular position.

Figure 12 is a section on the line 12—12 of Figure 11.

Referring to the drawings, the numeral 2 indicates the press as a whole which is shown as of the upright type. The press has mounted at the rear thereof an electric driving motor 4 having the shaft 6 on which there is rigidly secured the pinion 8. The pinion 8 meshes with and drives the gear wheel 10 secured to a shaft 12 which has the flywheel 14 secured thereto. The shaft 12 extends through the machine to the other side thereof and has the pinion 16 secured thereto. The pinion 16 meshes with a gear wheel 18 rigidly mounted on a shaft 20 mounted in bearings in the frame of the press 2. The shaft 20 has a cam 22 formed intermediate its ends which works in a journal 24 of the plunger 26 of the press. The rotation of the shaft 20 will rotate the cam 22 and cause the plunger 26 to move up and down. The plunger is guided by means of the slides 28 at the top and bottom portion thereof. The press has the usual bed 30 on which the mechanism 32 of the press is mounted. Except for the mechanism 32, the parts so far described are conventional and per se form no part of the invention.

On the bed plate 30 of the machine there is mounted a die shoe 34 of the mechanism 32. This bed plate extends through the machine and has mounted thereon the movable parts of the mechanism.

Referring to Figures 3 and 4, it will be noted that the bed plate is provided with enlarged ear portions 36 at the sides thereof and in each ear portion there is rigidly mounted the lower end 38 of a guide rod 40, the upper end of which acts as a slidable mount for a bearing 42 mounted in the arms 44 extending from the head 46 (Figure 5) secured to the plunger 26. Secured to the head 46 as at 48 (Figure 6), is the yoke 50 the arms 52 of which are offset at an angle to the

base of the yoke and project downwardly on opposite sides of the machine as best shown in Figures 3 and 5. The yoke arm will therefore move with the plunger 106 and partake of the vertically reciprocatory movement thereof. The end of each arm 52 has mounted therein a pin or shaft 54 threaded at its outer end to receive a nut 56. Its inner end is enlarged as indicated at 58 and a cam roller 60 is mounted thereon and held in place by the enlarged head 62. The shafts or pins 54 are held in place by a suitable cap 64 and adjusting screws indicated as 64a. The purpose of this structure at 64 is to raise or lower the roller in order that it may work in timed relation to operate the cams 66.

One cam 66 is provided at each side of the mechanism and each cam has the sliding base 68 and slides in the guideways 70 and 72 secured to the base 34 by means of machine bolts. Each cam has the cam slot 74 (Figure 6) therein and in each cam slot a bearing or wear member 76 is mounted. The head ends of the shafts 54 and the rollers 60 are mounted in the slots 78 of the bearing members 76 and as the yoke 50 moves vertically, the shaft 54 and roller 60 will move in the slot 78 to impart to the cams 66 a horizontally reciprocatory movement. Each cam has secured to the base 68 by means of the machine bolts 80 a cam extension bar 82 which extends the full length of and slides in guides in the base of the machine and partakes of the movements of the cams.

Mounted immediately adjacent the cam extension bars 82 and face to face therewith are the feeder bars 84 which have both a vertical and horizontal reciprocatory movement. The feeder bars are mounted in the guideways 72 at the front of the machine and in other suitable guideways at the rear of the machine. The cam extension bars 82 and the feeder bars 84 are united to each other by means of a pin and inclined slot connection indicated as a whole at 86 (Figure 6). The pins 88, with a roller 90 secured on each, are permanently mounted on the extension bars 82 while the slots 92 are inclined all in the same direction and are provided in the feeder bars 84. As many of these pins and slot connections as desired may be provided. In the present instance, two have been shown, one at the front and one in the rear of the machine. The bars are further connected by means of the structure 81 shown in Figures 7 and 10. The extension bars 82 have openings 94 therethrough each to receive a steel ball 96 and a spring 98, both being retained in position by means of the cap 100 threaded into the extension bar 82. The feeder bars 84 have elongated depressions 102 to receive the ball. In the full line position in Figure 10, the ball is shown in the uppermost depression and holds the two members 82 and 84 together so that, unless prevented by other forces, they will rise and fall together. In the dotted line position 104 the feeder bar 84 has been moved upwardly so that the ball 96 seats in the lowermost depression to retain the members 82 and 84 in this position. The length of the depressions 102 corresponds to the length of the slots 92. While there has been shown but one of these mechanisms of Figure 10 for each pair of bars, as many as are desired may be used. Preferably, there is one at the front and one at the rear of each extension bar.

Referring to Figures 3, 6 and 7, it will be noted that at the front of the machine a plunger 106 has been mounted on the base 34. The plunger is

contained in a housing 108 and a spring 110 urges the plunger downwardly or out of the housing. At the rear of the machine on the base a second plunger 112 is mounted in a housing 114 and has a coil spring 116 constantly urging the plunger 112 upward. The plunger 106 is limited in its downward movement by means of the nut 118 and the plunger 112 is limited in its upward movement by means of the head 120. The plunger 106 projects into the path of movement of the feeder bar 84 while the plunger 112 projects into the path of the feeder bar 84 and at times is received in a recess 122 formed therein.

The movement of the cam 66, cam extension bar 82 and feeder bar 84 and the cooperation of the pin 88 and slots 92 and the plungers 106 and 112 will now be described when considering Figure 8 which shows the various positions of the parts during the respective movements. The parts will be described in their sequence and they are designated in Figure 8 as in positions 1 to 5, inclusive, position 5 being the same as position 1. Position 1 is indicated in full lines and shows the position of the parts when the die has performed its work and is about to leave the work and move upward. The upward movement of the die will carry therewith the pin and roller 54, 60 which will move vertically for a short distance in the vertical portion 78a of the slot 78 so that there will be no movement of the cam 66 or bars 82 and 84 during this short ascent of the yoke 50 and pin and roller 54, 60. When the roller 60 strikes the curved or inclined portion 78b of the slot 78 the action of the roller on the cam slot will move forward the cam 66 and the cam extension 82 permanently secured thereto. The feeder bars 84 will be in their lowermost position and will endeavor to move along with the cam extensions 82 but owing to the fact that the plunger 112 is in the recess 122 of the feeder bar, the bar will be prevented from moving in a horizontal direction. The action of the pin 112 and recess 122 will bring the pins or shafts 88 and their rollers 90 into play and press against the sides of the inclined slots 92. This action of the rollers 90 on the sides of the slot 92 will force the feeder bars 84 upward or toward the dotted line position indicated as position 2. When the feeder bar has reached position 2 the cam 66 will have moved from the full line position, or positions 1 and 5, to the dotted line position indicated as position 2 and will have raised the feeder bar recess 122 away from contact with the plunger 112. This raising of the feeder bar 84 relative to the extension bar 82 will move the feeder bar from the full line position in Figure 10 to the dotted line position 104. During this vertical movement the ball 96 will be pushed from the upper depression 102 and ride on the surface between the depressions and be pressed by the spring 98 into the lower depression 102. Inasmuch as the feeder bar 84 is now clear of the plunger 112 and as it is held on the extension bar by means of the structure shown in Figure 10 it will move with the extension bar horizontally to position 3. When the two bars and the cam 66 have reached position 3, the plunger 106 at the front of the machine will fall or be thrust behind or in the path of the feeder bar 84. During the change in position from 1 to 2 the feeder bar will have raised the work from the dies and moved it along one step to its next position or, in case the dies have performed their final operation, the work will be removed from the machine entirely.

When the parts are in position 3 the die is com-

Referring to Figures 6 and 7 the details of the dies are best shown. At station 202 the dies comprise the upper member 214 and the lower member 216 held to the plunger 26 and bed plate 34, respectively, by means of the machine bolts 218. Each die comprises two similar forming portions 220 but only one of these portions act on a piece of stock at a time. The reason for this is the alternate distribution of the work by the distributor 148. In Figure 6, the piece of work is shown in the right-hand die but the next piece of work will be delivered by the feeder bars to the forming portion 220 at the right of the figure. The reason for this alternate distribution is to avoid excessive wear on one set of dies.

At die station 204 complementary upper and lower die portions are provided but at this station the upper and lower knock-out bolts or bars 222 are provided. The purpose of these knock-out bolts is to remove the work from both upper and lower dies for the reason that it has been found that the work at times will stick to one or the other of the dies and prevent the feeder bars from moving it along through the machine. The knock-out bolts have suitable coil springs 224 to withdraw the bolts into the openings in timed relation with the operation of the dies. The lower bolts 222 (Figure 7) have the plate 226 therebelow which operates at a suitable time to push the bolts upward to knock the work out of the lower dies. The mechanism for operating the plate 226 is conventional and forms no part of the invention. Similarly the upper portion of the die has the plate 228 which is operated in suitable timed relation by the plunger 230 to kick or knock off the work from the upper set of dies.

At station 206 no lower knock-out bolts are necessary for the reason that the dies 232 punch the work out of the piece of material and force it through the openings 210 or to the table 212. The upper portion of the die, however, has the stripper plate 234 operated by the plunger 230 through the plate 238 and pins 238 to push the scrap 208 from the dies as the plunger 26 as- cends.

The dies are mounted on a die member or block 238 which is held to the plunger 26 by means of the bolt and nut connection 240 (Figure 3) and suitable means is provided for intermovement between the plunger 26 or the die member 200 and the plates 228 and 238. Suitable coil or other springs 242 are provided between the plate 238 and punch holder 46.

For purposes of clearer illustration the structure of Figures 11 and 12 has not been shown on the other views but it is applied to the machine at the sides of the die stations 202, 204 and 206. The structure is advantageous when the press is working rapidly because of the tendency of the work to bounce from the dies when the plunger 26 is raised. This bouncing and misplacement prevents the accurate positioning of the work at the next station. The structure is shown applied to two stations but it may include all three.

Secured to the bed plate 34 at the side near the top thereof are a plurality of angle arms 244 each having a roller 246 in the end of the arm. Each arm is secured by a machine bolt 248. The rollers 246 are positioned in L-shaped slots 250 in a retainer 252 which is angle shaped and has its horizontal angle arm 254 extending over the horizontal angle 256 of a second angle member 258 secured to the feeder bars 84 by the machine screws 260. The member 258 necessarily partakes

of the movement of the feeder bar. The retainer 252 and member 258 are constrained to move together longitudinally by the pegs or pins 262 which are rigidly mounted in the member 258 and slide in openings in the retainer 252.

The full line position of the parts in Figures 11 and 12 shows them in the position they occupy when the feeder bar 84 is raised a distance through about one-half its total vertical movement. The rollers 246 are shown in the smaller leg 264 of the L-shaped slots 250. The dotted line position 266 shows the lowermost position of the feeder bar 84 and angle member 258 and the dotted line position 268 shows the uppermost position of the retainer 252. The dotted line position 270 shows the extreme left-hand position of the angle member 258 and the dotted line position 272 shows the extreme left-hand position of the retainer 252. When the dies are performing their work, the feeder bar and the angle member 258 are in the position 266 and the retaining member 252 is substantially in the position shown in full lines in Figure 11. When the upper or movable dies rise with the plunger, they will take the pressure from the flange 254 and the weight of the retainer 252 will hold the blank or material to be forged on the dies. The feeder bar 84 will now rise until it comes in contact with the work and will then lift the retainer member 252 from the work and cause the slot 264 to ride over the roller until the roller rests at the bottom of the slot 264 or in the slot 250. The feeder bars will now move the work 134 and the retainer member 252 to the left until it reaches the dotted line position 272. The feeder bars 84 then move downwardly to the position 270, the retaining member 254 being held in elevated position by the rollers 246 which are now at the extreme right-hand end of the slots 250. The feeder bars now move to the right to the position 266 and carry therewith the retainers 252. When they reach the position 266 and 268, the retainer members 252 may fall or drop because the rollers have again reached the shorter slot 264 and may now rest on the work firmly to hold it in position. The feeder bars 84 now descend to allow the plunger to operate the dies. When they reach the work the die block 200 rests on the flange 254 to hold the retainers on the work. It will, therefore, be seen that the structure of Figures 11 and 12 accomplishes the retaining of the work in position on the dies while the machine operates and prevents the work from bouncing due to rapid operation.

I claim:

1. A forging machine including a base, a blank supply zone and a plurality of forging zones spaced along the base, each forging zone including a stationary die and a movable die adapted to operate on pieces of stock positioned transversely of the base, a feed bar on each side and extending along the base, means on the feed bars located at each of said zones adapted to receive the projecting ends of the pieces of stock there positioned, means to raise said feed bars to receive the ends of the stock at the forging dies and lift the same vertically therefrom as well as to receive a new piece of stock from the supply, means to cause horizontal movement of said bars simultaneously to advance all said pieces of stock to succeeding zones along said base, means to lower said bars to release said pieces of stock, and means to cause the bars to return along a generally horizontal path in lowered position.

pletely raised and the pin and roller 54, 60 are at the top of the cam slots 78. The next movement of the plunger 26 will be downward and will move the pin and roller 54, 60 downward in the slot 78. 5
15 This downward movement will act on cam slots 86 to move the cam 66 in a rearward direction to position 4. The extension bar 82 will, of course, move with the cam but inasmuch as the plunger 106 is in the path of the feeder bar 84 the feeder 10
10 bar will be unable to move until the roller 90 and cam 92 act to move the feeder bar downward to remove it from the influence of the plunger 106. In moving the parts from position 3 to position 4 the feeder bar 84 will move from the dotted line 15
15 position in Figure 10 to the full line position and in this movement it will depress the plunger 112. The feeder bars 82 and 84 will now move together to the right to position 5 which is the same as initial position 1. When it has reached position 5, 20
20 the recess 122 will be over the plunger 112 which will be forced thereinto by means of the spring 116 therebeneath. The four operations described will pick up and move in a horizontal direction and then deposit the work or finished article to a 25
25 new position.

Referring to Figures 7 and 8, attention is called to the fact that the upper portion of the base of the machine ends at 124 and beyond which there is a space between the feeder bars and below this 30
30 space there is the grid or spaced bars 126. These bars are equally spaced and there is adapted to move therebetween the bars 128 forming a table 212. The bars 128 are attached to the feeder bars 84 by means of the legs or strips 130 and 35
35 suitable crossbars so that the bars 128 will partake of the movement of the feeder bars 84. In partaking of this movement, the bars 128 will pick up and move along in a step by step movement, the finished articles or pieces of work shown at 40
40 132.

Referring to Figures 3 and 6, inclusive, the mechanism and manner in which the work or pieces of stock 134 are fed to the machine will be described. An inclined table or hopper 136 is 45
45 rigidly secured to an upright 138 of the bed by means of the supports 140. The table has the round or curved portion 142 at its lowermost end, the purpose of which is to hold the bars of stock and prevent them from rolling on to the horizontal table 144. The table 144 has mounted at its sides the guide plates 146 which guide the pieces of stock into the distributor indicated as a whole at 148. The side members 146 also form the sides of the distributor 148. The table 144 is 50
50 shown as mounted by means of the supports 150.

Journalized in the enlarged portion of the side plates 146 at the distributor 148 is the distributing wheel indicated as a whole at 152. This distributing wheel is best shown in detail in 55
55 Figures 5 and 6 and comprises the end bearings 154 mounted to rotate in the enlarged portions of the side plates 146. In the bearings 154 there is mounted the distributor plate 156 and the bearings 154 are held in place by means of the hubs 158 having their peripheries formed into four teeth 160. The point of each tooth is in turn grooved as at 162 (Figure 3) and in the groove 162 there is received the pointed end of a plunger 164 mounted in the barrel 166 and spring-pressed 60
60 into engagement with the grooves. The barrels are secured to the side plates 146. The end of the table 44 is formed to the shape shown at 168 and a two-part spacer 170 forms the top and left-hand side of the distributor (Figure 6). Two 65
70 channel-forming members 172 are positioned 75
75

below the distributing wheel 152. The parts 168 to 172 form the two channels 174 and 176 and below the channels there are the grooves 178 and 180 in the bed 34. Between the two parts 170 a retaining bar 182 is positioned and this bar rides upward in the space 184 between the spacer member 170. In its normal position shown in Figures 5 and 6 it prevents the bar of stock 134 from dropping on to the distributor board 156. A cam 186 on the hub 158 operates in timed relation with the other mechanism to raise the stopper bar 182 to allow a piece of the work 134 to roll on to the distributor board 156 and depending upon the position of this board, the piece of work will roll into one or the other of the channels 174 and 176. 15

The feeder bars 84 have attached thereto the arms 188 and 190 (Figure 6), the upper ends of which have semicylindrical notches 192 and are adapted to pick up the lowermost piece of work 20
20 136a from the inclined hopper 136 and move it forward one step. Successive operations of the feeder bar will move the work over to the distributor where the bar will roll down against the stopper bar 184. As the cam 66 reciprocates, it 25
25 will move therewith a tooth 194 pivoted on a bolt 196 mounted in a bracket 197 secured to the cam. The tooth 194 is in the path of the teeth 160 of the hubs at the ends of the distributor. As the tooth 194 strikes one of the teeth 160 it 30
30 will rotate the distributing wheel 152 to 90° and shift the distributor plate 156 from the full line position shown in Figure 6 to the dotted line position, and cause the plunger 164 to catch in the groove 162 of the next tooth 160. This change 35
35 in position will cause the piece of work to fall into the channel 174 instead of the channel 176 and distribute it into the groove or notch 178 instead of the notch 180.

The feeder bars 84 are provided on their sides 40
40 with suitable notches 198 at the various stations to pick up and move the work forward step by step and such notches are provided on the bars opposite the grooves or notches 178, 180. It will, therefore, be apparent that when the machine is in operation, the cam 66 and tooth 194 will operate the distributor to feed the work alternately into the grooves 174 and 176 and the operation of the feeder bars will carry the work from this position to the dies indicated as a whole 45
45 at 200 and which comprise three separate sets of dies 202, 204 and 206, best shown in Figures 4, 6 and 7. Each set of dies comprises the upper movable dies on the plunger 26 and the lower stationary dies mounted on the bed 34. The bars of stock 50
50 134 are, of course, heated before they are fed to the hopper and they arrive at the first set of dies 202 in the form shown at 134 in Figure 9. The first operation in the station 202 forms the stock into substantially the shape shown at 134x. From this station the feeder bars move the formed member 134x to die station 204 where they are formed to substantially the shape shown at 134y in Figure 9. From die station 204 the feeder bars move the forged work to die station 206 55
55 where the dies sever the finished articles 132 from the scrap or excess material indicated in Figure 7 by the numeral 208. The finished article 132 drops through the openings 210 on to the table or bed 212 formed by the bars 126. The scrap material 208 is successively moved along by the feeder bars and eventually falls on to the table 212 where it is moved along with the scrap metal to the rear of the machine where the two are separated. 70
75

2. A machine according to claim 1, each of the dies having a plurality of forming portions, and means adapted to feed successive blanks to different positions to be engaged by the feed bars whereby the feed bars deliver said successive blanks to different forming portions of the dies.
3. A machine according to claim 1, and means secured to the movable die and operatively engaged with the feed bars to move the same and to cause the feed bars to operate in timed relation with the movement of the dies.

HUGH DEAN.

5
